Primary Examiner—Joseph S. Reich
Attorney—William H. Finckel, Jr.

ABSTRACT: A smoking device primarily for cigarettes and the like, comprising an ash tray provided with a holder for a cigarette or the like extending upwardly therefrom in such a position that the ashes from the cigarette or the like will fall into the tray as the cigarette or the like is consumed, a smoking tube connected with the said holder and extending from and beyond the ash tray so that the smoker may mount the smoking device relatively remote from his smoking position, a plurality of adapter members of severally different interior sizes and forms assemblable with said holder for adapting the holder to the reception of cigarettes and the like of different diameters and cross-sectional shapes, means for affixing the device to a supporting member, such as a table or bracket, and, per choice, a pivotal connection between said holder and ash tray whereby the holder and tray may be folded into compact arrangement for disposition in a constricted space such as a garment pocket or hand bag.

SMOKING DEVICES

The present invention embodies modifications of, and improvements over, the similar devices disclosed in the U.S. Pat. of James P. Kiernan, No. 2,093,760, granted Sept. 21, 1937, and applicant's own U.S. Pat. No. 2,910,986, granted Nov. 3, 1959.

A primary object of the invention is to provide means for modernizing the smoking device of the Kiernan patent just above referred to so that it will accommodate not only cigarettes of the conventional, or standard, type of rather large diameter but also the more modern types of smaller diameter, filter tip cigarettes, extra length cigarettes, and cigarettes of oval shape in cross section.

Another object of the invention is, broadly, to provide a smoking device including an ash tray and a holder for a cigarette or the like which may be located adjacent to the smoker and is provided with a tube, preferably of flexible type, connected with the holder and provided with a mouthpiece and through which smoke is drawn from the cigarette or the like to the mouth of the smoker, thus making possible mounting of the smoking device on a table, bracket or other support relatively remote from the smoker and facilitating smoking without the danger of fire from hot ashes and sparks falling from the cigarette or the like onto the clothing, bed clothes, furniture upholstery and the like often present in smoking by invalids, disabled persons and others who cannot readily serve themselves.

Another object is to provide a smoking device of the type referred to, the holder of which is foldable into proximity to the ash tray so that when the device is not in use it may be disposed in compact form for carrying in the owner's clothing pocket, hand bag or the like.

A further object is to make the device suitable for the reception of a variety of shapes and sizes of cigarettes now extant and hereafter developed, such as those of small diameter, oval shape in cross section, more than normal length, and filter type, and also for cigars and for accommodation of a pipe bowl member, these modifications being effected by the provision of a plurality of adapters for selective accommodative attachment to the holder.

Another object is to provide means in the holder for the ejection therefrom of the butt of a cigarette or the like, such means being effective whether the cigarette or the like is inserted in the holder proper or in a selected adapter attached thereto.

The length of some cigarettes, and of cigars, is such that the ashes falling therefrom during smoking might not be caught in the ash tray of the device in its normal size, and to accommodate the device to this further eventuality another object is to provide a supplementary ash tray member larger than that of normal size for disposition beneath and connection to the normal ash tray.

Still another object is to adapt the device for attachment to a stand, bracket, table, or other support, not only to insure that it will not be displaced, particularly when used by a disabled person, but also to guard against theft. Moreover, such attachment will preferably be of a nature releasable at the will of authorized persons, so that the device may be appropriately cleansed and sterilized, particularly in its use in the rooms of hospitals and other public accommodations, as on a bedside table or other support, this attachment being provided for by a knockout area in the ash tray for the reception of a bolt or the like, the securing means of which, such as a wing nut, may be sealed or locked against removal.

With these and other objects in view, the invention comprises a smoking device including an ash tray, a holder for a cigarette or the like assembled with said tray and extending upwardly therefrom, a flexible tube extending outwardly from said tray in suction-affording connection with said holder, said holder having an internal diameter preferably such as to snugly fit the end portion of a chosen type of cylindrical cigarette and furnishing a suction-affording assembly of such cigarette therein, adapter means assemblable with and extending beyond the outer end of said holder and serving to adapt

the holder to cigarettes or the like of diameters and cross-sectional form different from that aforementioned, cigarette butt ejector means set axially within the holder and affording a fixed connection with said ash tray and with respect to which the holder is axially slidable to an extent sufficient to eject a butt from the holder, means rigidly but removably mounting said smoking device upon a suitable support, and a supplementary ash tray of greater area than the tray of said device and capable of assembly therewith to adapt the device to service with extra long cigarettes and cigars, all as will be explained hereinafter and finally claimed.

In the accompanying drawings illustrating the invention, in the several FIGS. of which like parts are similarly designated:

FIG. 1 is a top plan view of the smoking device with a part of the smoking tube broken away and showing one type of adapter assembled with the cigarette holder;

FIG. 2 is a sectional elevation of the device taken substantially on the line 2-2 of FIG. 1, looking in the direction of the arrows;

FIG. 2a is a fragmentary sectional elevation of a modified form of the invention in which an adapter member is applied to a smoking device of known form;

FIG. 2b is a view similar to FIG. 2a but showing the parts in a different adjustment;

FIGS. 3, 4 and 5 are, respectively, a top plan view, a bottom plan view, and a sectional side elevation view, with parts broken away and shown in section of another type of adapter particularly for the reception of a so-called oval type of cigarette;

FIG. 6 is a sectional side elevation of an adapter for the reception of a cigar or cigarillo;

FIG. 7 is a sectional side elevation of an adapter in the form of a pipe bowl;

FIG. 8 shows, in sectional side elevation, a modification of the means of connection between the ash tray and the cigarette holder, same including a ball and socket joint for pivotal mounting of the said holder whereby it may be folded into close proximity to the ash tray;

FIG. 9 is a fragmentary sectional side elevation of a modified form of ball and socket joint for connection of the cigarette holder with the ash tray;

FIG. 10 is a sectional side elevation view, with parts broken away and shown in section, on a smaller scale, showing one form of means for fixedly assembling the smoking device with a suitable support such as a table top;

FIG. 11 is a view similar to FIG. 10 but showing the device attached to another form of support such as a bracket;

FIG. 12 is a fragmentary elevational view showing the device as attached to a bracket secured to a supporting member such as the steering column of an automobile, a bed post or the like;

FIG. 13 is a top plan view, on a scale similar to that of FIGS. 10 to 12, showing the smoking device assembled with a supplementary ash tray of larger diameter than that of the device itself;

FIG. 14 is substantially a diametrical sectional view of the parts shown in FIG. 13;

FIG. 15 is a rear elevation of the supplementary tray shown in FIGS. 13 and 14 and illustrating one embodiment of means for providing a connection between said tray and the smoking device; and

FIG. 16 is a view similar to FIG. 15, but showing another embodiment of the connection means.

Having reference particularly to FIGS. 1 and 2, it will be seen that the device of the invention includes an ash tray 1 preferably in the form of a relatively heavy, and normally stable, metal disc having its upper surface of dished form and provided with a screw-threaded angularly disposed, socket 2 for the reception of the complementally screw-threaded lower end of the holder supporting tubular member or cylinder 3 on which is mounted for axial sliding movement the cigarette holder member 4 guided at its upper end by the cigarette butt ejector member 5 which is rigidly mounted upon the upper

end of the supporting cylinder 3 by a hollow rivet 6 having its head 7 engaging a shoulder 8 formed in the bore of the cylinder 3 and its shank press-fitted into the bore 10 of the ejector member 5 the lower end of which bears against the upper face of the shoulder 8. Between the upper end of the cylinder 3 and a shoulder 11 formed interiorly of the cigarette holder member 4 is arranged a return spring 12 which serves normally to force the cigarette holder member 4 into its outwardly extended position, the outward movement of the said holder member 4 being limited by a head 13 on the outer end of the ejector member 5 which engages the upper face of the shoulder member 11. This head 13 is provided with a screwdriver notch 14 by means of which a screwdriver may be employed to assemble and disassemble the cigarette holder proper in the ash tray.

In the embodiment shown in FIGS. 1 and 2, the diameter of the interior of the cigarette holder member 4 and of the head 13 of the ejector member 5 is such as to form a socket having a relatively tight, suction-affording, fit with a cigarette of the smallest diameter normally used. Thus, when such a cigarette is used no adapter member for the holder member 4 is necessary. When, however, a cigarette of larger diameter is used an adapter member 15 may be screwed onto the screw-threaded end of the holder member 4, as is shown in FIGS. 1 and 2, and the lower end of such cigarette will seat against the upper end of the holder member 4, as indicated in broken lines.

It will be apparent that provision is made for sufficient downward sliding movement of the holder member 4 to accomplish ejection of the cigarette butt from either the socket of the holder member 4 or from the socket portion of the applied adapter 15, and this will be accomplished simply by grasping with the fingers either of these members 4 or 15 and sliding the holder member 4 downwardly upon the ejector member 5 against the pressure of the spring 12, and, obviously, release of the holder member 4 will permit the spring 12 to return it to its normal cigarette-holding position.

It should be here noted that the screw thread at the outer end of the holder member 4 is purposely quite fine and that the surface of the adapter 15 (FIG. 1) is knurled thus to afford a firm grip of the fingers upon either of these parts without the exertion of undue pressure, and this is important in relation to users with tender or sensitive skin, nervous persons and invalids.

The bores of the supporting cylinder 3, rivet 6 and ejector member 5 form an adequate suction-affording passage between the cigarette-holding portion of the holder member 4 (and an applied adapter, if one is used) and a counterbore 16 in the ash tray 1 which intersects the socket 2 is screw-threaded to receive the complementally screw-threaded end of a ferrule 17 which is shouldered at 18 for abutment against the periphery of the ash tray 1 and serves to connect in suction-affording assembly the flexible smoking tube 19 which is provided with a mouthpiece 20.

It will be understood that any of the adapters 21, 22 and 23 shown in FIGS. 3 to 5, 6 and 7, respectively, or others as circumstances may dictate, may be substituted for the adapter 15, and that, particularly as related to the adapters of FIGS. 3 to 5, and 6, the ejector member 5 will serve to eject the butt of a cigarette or the like from the holder.

In FIGS. 2a and 2b the adapter means of the invention are of such form, and so applied to the cigarette holder member 4a of a smoking device of known form, such as that shown in the U.S. Pat. of Kiernan, No. 2,093,760 hereinabove referred to, as to permit effective functioning of such a smoking device when used with cigarettes of diameters less than those which have for years been conventional. In such known smoking devices the internal diameter of the cigarette holder 4a is such as to form a proper suction-affording fit with the end portion of a conventional cigarette, but it will not provide such a fit with the presently popular small-diameter, extra long, and filter tip cigarettes.

Therefore, to answer the need presented by use of the smoking device with such last named types of cigarette the

adapter 15a is provided with a socket portion having a constricted outer end portion 15b which will effect a proper suction-affording fit with the end portions of such cigarettes. Obviously, such cigarettes may be inserted to an extent to contact their ends with the outer face of the head 13a of the ejector member, and ejection may be effected by sliding the holder 4a downwardly upon the cylinder 3 in a manner similar to that described in relation to FIG. 2.

Inasmuch as the outer end portion of the adapter 15a will not be reached by the head 13a of the ejector member during the ejecting operation, the constricted portion 15b will preferably be chamfered as shown at 15c to aid in release of the cigarette butt and usually to permit it to topple from the holder.

As indicated in FIG. 2b, the adapter member 15a may, if necessary or desired, be adjusted upon the screw thread at the end of the holder 4a to afford adequate extension of insertion of the end portion of the cigarette in the holder.

It will be understood that adapters of the types shown in FIGS. 3 to 5, 6 and 7, and others as need may arise, may be in forms to be applied to the cigarette holder shown in FIGS. 2a and 2b. Hence, smoking devices of the aforementioned known type, now in use or to be used, may be so modified as to accommodate all types of cigarettes, and also cigars and cigarillos, and pipe bowls.

Referring to FIG. 2, particularly, it will be seen that the angle at which the holder member 4 projects upwardly from the ash tray 1 serves to so locate the burning end of the cigarette throughout its smoking at a position above the ash tray which will serve to deposit the falling ashes and sparks in said tray. However, referring to FIGS. 13 to 16, it will be seen that the device is adapted to the reception of extra long cigarettes, and also cigars, by the provision of a supplementary tray 24 having an upstanding rim 25 and in which the ash tray 1 of the device is disposed in contact with the inner peripheral surface of the rim 25 of the supplementary tray 24 and is secured in such position by engagement of the shoulder 18 of the ferrule 17 of the smoking tube 19 with the outer periphery of such rim 25, either in a slot 26, FIGS. 14 and 15, or a circular opening 27, FIG. 16, provided in such rim 25 for reception of the screw-threaded end of the ferrule 17 and being of such size that the shoulder 18 cannot pass through but will abut against the rim in clamping engagement therewith.

Obviously, when the supplementary tray of FIG. 16 is employed, the ferrule 17 of the tube 19 will have to be completely removed from the ash tray 1, inserted through the opening 27 in the rim 25, and screwed back into the ash tray. But when the supplementary tray of FIG. 15 is used it is merely necessary to back off the shoulder 18 of the ferrule 17 sufficiently to permit entrance of the ferrule into the slot 26 and then seat the shoulder 18 of the ferrule against the rim 25.

Referring to FIG. 8, it will be seen that the means for supporting the cigarette holder upon the ash tray includes means whereby the cigarette holder may be folded down into close relation to the ash tray to thereby make the device more compact for carrying upon the person of the user, as in a garment pocket, hand bag or other depository. In the form shown, the supporting member 28 for the holder member 4 includes a ball and socket joint the ball 29 of which seats in the lip 30 of a collar 31 interiorly screw-threaded at 32 for engagement therewith a ball-engaging sealing member 33. It will be apparent that the diameter of the screw-threaded portion 32 of the collar 31 is such that it may be slipped over the screw-threaded end of the supporting member 28 and thence into engagement of its lip 30 with the surface of the ball 29.

In the modification shown in FIG. 9, the parts 31 and 33 of the FIG. 8 form of joint will be replaced by a drawn sheet-metal socket member 34 having its lower rim or skirt 35 spun into appropriate retaining and sealing engagement with the ball, a slot 36 being provided in its wall so that, upon folding down of the cigarette holder member 28 it will clear the necked-in portion of the supporting member 28. At its upper, or outer, end, the socket member is enlarged to provide seating for a

sweated-in screw-threaded collet 37 into which is screwed the lower end of the cigarette holder supporting member or cylinder.

In order that the device may be secured to a table, bracket, or other support, the ash tray is so made that its center portion is relatively thin, and in this portion a series of spaced cuts 38 (see FIGS. 1 and 2), preferably circularly arranged, is provided to define a knockout 39 similar to those employed in electrical outlet boxes and by which an opening may be formed. As shown in FIG. 10, a bolt 40 passed through such opening and through a mating opening in a table or other furniture top 41, with its head engaging the surface of the ash tray, will be secured as by a wing nut 42, or the like, bearing against the under face of the table top. As shown in FIG. 11, a similar arrangement may be employed in respect to a suitable bracket 43, and in FIG. 12 such a bracket may be a part of, and adjustable with respect to, attachment means for disposition of the device adjacent to the steering wheel of an automobile, for example on the steering column 44, and a similar bracket might be used on the bedpost of a metal, or other, bed.

Referring further to FIGS. 10 and 11, it will be seen that the bolt 40 has a transverse opening near outer end, as indicated at 45, for attachment of means for locking the device against detachment from its mounting and its possible theft, particularly when it is furnished in public accommodations. In FIG. 10 the locking means is shown as a more or less conventional wire seal 46, and in FIG. 11 it is shown as a small padlock 47.

Means, not shown, for providing a knockout in the supplementary tray 24 similar to that of the ash tray 1, but appropriately disposed radially inward from the opening 26 or 27, may be provided for furnishing an opening to insure proper relative disposition of the trays 1 and 24 in combination, especially when they are rigidly mounted on a support.

I claim:

1. In a smoking device, an ash tray, a holder for a cigarette or the like assembled with and extending above the said tray, and a flexible smoking tube extended outwardly from said tray and in suction affording connection with said holder, said holder comprising a tubular supporting member affixed to said tray and in communication with said tube, a tubular cigarette holder member mounted for axial sliding movement on said supporting member, a cigarette butt ejector member disposed interiorly of said holder member and in fixed relation to said supporting member, and resilient means reacting between said butt ejector member and said holder member for normally maintaining said holder member in upwardly extended position but permitting its downward sliding for butt ejection, said holder member having an internal diameter substantially consonant with the outer diameter of a chosen type of cigarette

and providing a socket for the retention of the lower end of said cigarette within the upper end portion of said holder member in suction affording assembly and in ejecting proximity to the upper end of said butt ejector member, and an adapter member removably and rigidly attached to the upper end of said holder member and having a socket portion for the reception in suction affording assembly of a type of cigarette having a different diameter or cross-sectional shape from that adapted for reception by the socket of the holder member and said socket portion extending above the upper end of said holder member, said supporting member being of sufficient length so that said holder member and the rigidly attached adapter member are downwardly reciprocable upon said supporting member to an extent sufficient to substantially eject a cigarette butt from the socket of said holder member and from the socket portion of said adapter member.

2. In a smoking device as defined in claim 1, means in the assembly between said holder and tray which will permit pivotal movement therebetween so that the holder may be disposed in compact relation to the tray substantially parallel thereto to thereby adapt the device to relatively flat-folded form for disposition in a constricted space such as a garment pocket or hand bag.

3. In a smoking device as defined in claim 2, said pivotal movement permitting means including a ball and socket joint.

4. In a smoking device, an ash tray and means for providing a holder mounted in said tray for receiving a cigarette or the like in smoking position with the consumable end of the cigarette overlying the area of the tray, a smoking tube extending from the ash tray and in suction-affording connection with said holder and having a shouldered ferrule abuttable against the periphery of said tray, and a supplementary ash tray of larger area than that of said device and designed to accommodate the device to the smoking of relatively long cigarettes, and of cigars, the ashes from the extreme ends of which might fall outside the area of the tray of the device, said supplementary tray being provided with an upstanding rim for engagement on its interior periphery with the exterior periphery of the ash tray of the device, said upstanding rim being provided with an aperture for the reception of the ferrule of said smoking tube, and a portion of said rim adjacent to said opening being engageable by the shouldered portion of said ferrule to secure the two ash trays together.

5. In a smoking device as defined in claim 4, the said aperture being in the form of a slot of a width of less dimension than that of the shouldered portion of said ferrule and extending through the upper edge of said rim.

6. In a smoking device as defined in claim 4, the said aperture being in the form of a circular opening of less diameter than that of the said shouldered portion of the ferrule.
